UNITED STATES PATENT OFFICE.

HERBERT CHRISTOPHER HEATH, OF WEMBLEY, EUGENE DAVID REGIS, OF STONEBRIDGE PARK, AND HAROLD GEORGE RUDDICK, OF ACTON, ENGLAND, ASSIGNORS TO GENERAL ELECTRIC COMPANY, A CORPORATION OF NEW YORK.

ELECTRIC SWITCH.

Application filed December 26, 1925, Serial No. 77,754, and in Great Britain January 15, 1925.

Our invention relates to electric switch installations and particularly to installations which include fluid break switches, and an object of our invention is the provision in 5 an installation of this character of improved means for receiving and cooling the gas expelled from the switches whereby an economy of space and manufacturing cost may be effected.

10 A preferred form of our invention relates to switch installations in which an elevated platform is arranged adjacent the switches for supporting apparatus such as isolating switches, switch operating mechanism, and 15 the bus bar system which is associated with the switches. In accordance with our invention the supporting base for the switches comprises the receptacle for receiving the expelled gases and the pillars by which the 20 platform is supported serve to convey the gases from the switches to the base.

Our invention will be better understood from the following description taken in connection with the accompanying drawing, 25 and its scope will be pointed out in the appended claims.

In the drawing, Figure 1 is a front elevation partly in section of a portion of a switch installation embodying our invention; and Figure 2 is a partial side view of the same also partly in section.

Referring to the drawing we have shown three switches 11 mounted upon a common bed plate 12 which is raised above the floor 30 or ground 13 by supports 14. The isolating switch chambers 15 and the bus bar chambers 16 are carried by the horizontal frame 17 comprising an elevated platform and this frame is supported upon vertical hollow pillars 18 resting on the bed plate 12. It is to be understood of course that switches 11, the isolating switch chambers and the bus bar chambers may be of any desired type, the drawing in this case being merely illustrative of one form or type.

Each pillar 18 is connected at its upper end by a pipe 20 with the interior of one of the switches 11. The space below the two right hand pillars 18 with which these pillars communicate is shown filled with a loose gas-cooling material 19 which for example may be gravel. If desired the gas-cooling material may be used only in the pillars as

shown in the left hand pillar 18 or if desired the gas-cooling material may be used 55 in both the base and the pillars.

When the switches operate to open the circuit controlled thereby the hot gases escape through the pipes 20 into the pillars 18. Where the pillars are open, such as 60 the two right hand pillars illustrated, the gases begin to expand and cool in the pillars but are more fully expanded and cooled in the space below, which is filled with the cooling material.

When two or more switch installations are arranged in proximity or in line the supports 14 may be provided with openings 21 to establish communication between adjacent base plates.

The switches may be provided with tops 22 carrying the terminals, which when the switch is to be removed may be lifted up to a position such as shown in dotted lines at 23, thus breaking connection with the pipe 20 at the place marked 24. If the switch is to be removed horizontally it is preferably severed from the supporting pillar at the place marked 25 which for this purpose should be a detachable joint.

What we claim as new and desire to secure by Letters Patent of the United States, is:—

1. In an electric switch installation comprising a fluid break switch, a platform supported thereover and a hollow-supporting 85 pillar for said platform connected to receive gases expelled from the switch.

2. In combination a fluid break switch, auxiliary mechanism arranged thereover, a hollow supporting pillar for said mechanism adjacent said switch and means forming a communicating passage between the switch and the supporting pillar.

3. In combination a fluid break switch, elevated auxiliary mechanism associated 95 therewith, a hollow supporting base for the switch adapted to receive and cool gases ejected therefrom and a hollow supporting pillar for the auxiliary mechanism connected to conduct the ejected gases from the switch 100 to the base.

4. In combination a plurality of fluid break switches, a platform arranged thereover, hollow supporting pillars for the platform arranged between the switches, and 105 pipe connections between the switches and

the pillars whereby the gases discharged from the switch may be delivered into the pillars.

5. In combination a plurality of fluid break switches, a hollow supporting base therefor containing gas-cooling material, disconnecting switches connected with the switches, a raised platform carrying said disconnecting switches, and a plurality of 10 hollow pillars for supporting the raised plat-

form, said pillars being connected with the switches and with the hollow base to conduct gases ejected from the switches to the base.

In witness whereof, we have hereunto set 15 our hands this fourteenth day of December, 1925.

HERBERT CHRISTOPHER HEATH.
EUGENE DAVID REGIS.
HAROLD GEORGE RUDDICK.
